UNITED STATES PATENT OFFICE.

JEANIE BEAR, OF PITTSBURGH, PENNSYLVANIA.

GARTER.

1,425,571.

Specification of Letters Patent. Patented Aug. 15, 1922.

Application filed November 30, 1921. Serial No. 518,823.

To all whom it may concern:

Be it known that I, JEANIE BEAR, a citizen of the United States, residing at Pittsburgh, in the county of Allegheny and State 5 of Pennsylvania, have invented a new and useful Improvement in Garters, of which improvement the following is a specification.

My invention relates to improvements in 10 garters used to support stockings, and particularly to ladies' garters.

The object of my invention is to produce an article of this character, which will efficiently support the stocking on the leg 15 without the use of a support connected to the corset. I accomplish this object by means of the device hereinafter more specifically described, reference being had to the accompanying drawings forming part 20 hereof, in which

Figure 1 is a perspective view of my improved garter, showing the manner of its application.

Figure 2 is a rear elevation of the garter. 25 Figure 3 is a side elevation of the same, partly in section.

Figure 4 is an elevation of the garter with value receptacle attached.

Referring to said drawings, 1 and 2 are 30 elastic bands, the band 2 being connected at the rear to the semi-elastic link 3 and the band 1 seated in the upper end of the link an appreciable distance from the band 2. The said band 1 is adapted to encircle the 35 leg above the knee, over which the upper end of the stocking 4 is adapted to be folded. The band 2, which is preferably wider and of less diameter than band 1, is adapted to encircle the leg below the knee. The elastic 40 or semi-elastic link 3, is disposed at the rear of the leg and under the knee joint, the bands 1 and 2 being disposed in said link or loop 3, the band 1 in the upper end thereof and the band 2 in the lower end, an ap-

preciable distance separating the said bands 45 when the article is in use, whereby when the leg is flexed the bands are maintained separate, thus preventing pinching, causing discomfort in the use of the garter. An adjustable means which in the particular in- 50 stance comprises the supplemental narrow band 5, attached to the band 2 and having eyelets 7, to receive the stud 6 on the band 2, whereby the slack occasioned by usage may be taken up, by tightening the band 5 55 sufficiently to bring the next eyelet therein into engagement with the stud adjacent to the one previously engaged. A receptacle 8, is slidably mounted upon band 1 and is adapted to contain jewels or other valuables 60 and to be securely concealed when the upper end of the stocking is folded over said band 1, as heretofore set forth.

Having described my invention what I claim and desire to secure by Letters 65 Patent is

A garter comprising two elastic members, each adapted to encircle the leg, one above the knee and the other below the knee, a flexible member connecting said upper and 70 lower members, the lower member being disposed at the lower end of said flexible connecting member and having a stud, and the upper member at the upper end of said flexible connecting member, means to take 75 up the slack in the lower member, including a supplemental band attached to and extending over said lower member, and having eyelets adapted to engage the stud on said lower member. 80

In testimony whereof, I have hereunto signed my name in the presence of two subscribing witnesses.

JEANIE BEAR.

In the presence of—

JOHN H. RONEY,
CORA J. NAUGLE.
